(57) **CLAIM**

The ornamental design for a polyclean dialysis station, as shown and described.

DESCRIPTION

FIG. 1 is a front perspective view of a polyclean dialysis station, showing my new design.

FIG. 2 is a front perspective view thereof, in slightly tilted position.

FIG. 3 is a rear perspective view thereof, with the cover removed.

FIG. 4 is a rear perspective view thereof, in use condition, the broken line showing of the plumbing being for illustrative purposes only and forming no part of the claimed design.

FIG. 5 is a front elevational view thereof.

FIG. 6 is a rear elevational view thereof.

FIG. 7 is a top plan view thereof.

FIG. 8 is a bottom plan view thereof.

FIG. 9 is a left side elevational view thereof; and,

FIG. 10 is a right side elevational view thereof.
